United States Patent Office.

IRENEUS DONALDSON, OF TOLEDO, IOWA.

Letters Patent No. 72,375, dated December 17, 1867.

IMPROVEMENT IN SULKY-PLoughs.

The Schedule referred to in these Letters Patent and making part of the same.

TO ALL WHOM IT MAY CONCERN:

Be it known that I, IRENEUS DONALDSON, of Toledo, in the county of Tama, and State of Iowa, have invented a new and useful Improvement in Sulky-Ploughs; and I do, hereby declare that the following is a full, clear, and exact description of the same, reference being had to the annexed drawings, making part of this specification, in which—

Figure 1 is a perspective view.

Figure 2 is a rear elevation; and

Figure 3 is a plan.

The same letters when used indicate the same parts.

My improvements relate to the construction and arrangement of the carriages of sulky-ploughs, and their character will appear from the following description and claims.

A represents any ordinary plough, which may be attached to the frame in the following manner: A beam, B, projecting behind the plough, is secured in front to a brace, connecting the plough-handles A². The rear of the beam B is connected with the top of the plough-handles by braces B'. A standard, C, is fastened in the angle formed by the mould-board and land-side, and bolted to the plough-beam A¹. The tongue is fastened to the braces D and D', the former being attached to the standard, C, and the latter to a brace extending from the front of the beam, where it is attached by a hinged joint to the axle E. The tongue-braces are so connected as to give it a free vertical play. The axle E is attached to the lower end of the standard, C, by a round pin passing through the lower end of the vertical arm E''. The wheel is placed on the opposite end of the axle, and its distance from the plough may be adjusted by the oscillation of the arm E'' on the pin, the axle being held in place, when adjusted, by a bolt, F, attached to the standard, C, and inserted into one of a series of holes in a plate on top of the axle. The axle rests on the beam A¹. The depth of the cut of the plough is regulated by means of the compound levers I I', having their fulcrum on the caster-wheels H H' in front of and behind the plough. The lever I is attached adjustably to a standard, B', on the rear of the beam B, and it is attached by a round pin to the lever I', which is fastened to a standard projecting from the front of the plough-beam. The lever I' projects behind the point of attachment to the lever I, and behind the standard, C, along which it may be moved vertically, its lateral motion being prevented by a guide carried around the standard. The cord K is fastened to the upper end of the lever I', and extending downward passes under a pulley on the plough-beam, and thence over and under pulleys placed on the ends of the oscillating arm L, which is pivoted near its centre to the axle. This arm may be actuated by a handle, L', which being raised, will draw up one end of the arm L, and depress the other, thereby shortening the cord which is attached to the axle near the wheel, and thereby drawing down the levers and raising the plough and frame on the caster-wheels, and reducing the depth of the cut. By moving the arm L in the reverse direction, the plough and frame are dropped, thus increasing the cut.

What I claim as my invention, and desire to secure by Letters Patent, is—

1. In combination with the plough and carriage-frame, the compound levers I I', and casters H H', placed in front and rear of the plough for regulating the cut, substantially in the manner set forth.
2. In combination with the driver's seat G, the oscillating arm L, cord K, and adjusting-levers I I', arranged substantially as and for the purpose set forth.

In testimony whereof, I have signed my name to this specification, in the presence of two subscribing witnesses.

IRENEUS DONALDSON.
